UNITED STATES PATENT OFFICE.

ADOLPHUS JOHN LUSTIG, OF NEW YORK, N. Y., ASSIGNOR OF ONE-FIFTH
TO LOUIS KAHN, OF SAME PLACE.

MOLD FOR CASTING COMPOUND INGOTS.

SPECIFICATION forming part of Letters Patent No. 352,476, dated November 9, 1886.

Application filed March 23, 1886. Serial No. 196,213. (No model.)

To all whom it may concern:

Be it known that I, ADOLPHUS JOHN LUSTIG, of the city of New York, county and State of New York, have invented a new and Improved Mold for Producing Compound Metal Plates, of which the following specification is a full, clear, and exact description.

This invention relates to a mold for producing compound metal plates consisting of graded and ungraded metals; and it consists of the various elements hereinafter described.

In the accompanying drawings, Figure 1 is a perspective view of the complete mold. Fig. 2 is a perspective view of the mold removed 15 from the base-plate, and part of the front plate removed. Fig. 3 is a perspective view of the base-plate. Fig. 4 is a cross-section of the same at line *y y*, Fig. 3. Fig. 5 is a vertical section at line *x x*, Fig. 1. Fig. 6 is a horizontal section at line *z z*, Fig. 1; and Fig. 7 is a perspective view of a bar placed upon the graded metal.

The mold A consists of the back plate, *a*, and side plates *b b*, with internal side plates, *b' b'*, some distance from the side plates *b b*, and closed by a front plate, *c*. Inside of the front plate, *c*, there is a wrought-iron sheet, *f*, between which and the front plate, *c*, asbestos *m* is arranged. This front plate, *c*, and wrought-iron plate *f* are fastened to the side plates *b b* by screw-bolts *d d*. The back plate, *a*, is likewise protected by a stratum of asbestos, *n*, which is secured by a wrought-iron plate, *a'*. The space between the inner side plates, *b' b'*, and 35 the outer side plates, *b b*, is filled with asbestos *b' b'*, and the inner side plates, *b' b'* are made of less depth than the outer side plates, so as to form, when the front part is attached, a recess for the reception of the metal plate to be compounded with ungraded metal.

This mold, constructed as above described, is placed into a sole-plate, *B*, consisting of a bottom plate, *g*, with upwardly-projecting back *h* and front *k*, in which latter a set-screw, *l*, is arranged to secure the mold A firmly to this sole-plate *B*. Upon the bottom plate, *g*, a stratum of asbestos, *w*, is placed. On top of this a cast-iron plate, *v*, is placed, upon which the mold A rests. The stratum of asbestos *w* prevents the 45 radiation of the heat, and the cast-iron plate

v, forming the true bottom of the mold A, prevents the coagulation of that part of the metal first poured into the mold.

The arrangement of the wrought-iron plate *f* on the inside of the front plate, *c*, with the stratum of asbestos *m* between them, is for the purpose of preventing by the asbestos radiation of the heat toward the outside of the box, and by means of the wrought-iron plate to distribute the heat which the gold-metal plate 55 receives from the first part of the liquid metal poured into the mold, on account of wrought-iron being a better conductor than cast-iron. The stratum of asbestos *b' b'* between the double sides and the stratum of asbestos *n* against the 60 outside of the back plate, *a*, prevent the radiation of heat from the inside of the box.

Into the recess formed by the diminished depth of the inner side plates, *b' b'*, as above described, the high-graded metal plate *M* to be 65 combined with ungraded metal is placed. To prevent the inpouring fluid metal from falling on the top of the metal plate *M*, a bar, *p*, is placed upon the same, having an upper surface slanting toward the inside of the mold. 70 Upon the top of the mold A a plate or cover, *C*, Figs. 1, 5, is placed, of such a length as to leave sufficient span on each end to pour this fluid metal into the mold A at the same time. By this cover the admission of cold air into 75 the mold at the time the fluid is poured in at each end is prevented, and consequently the cooling of the metal plate *M* and the oxidation of the metal is also prevented.

This mold may likewise be used for casting 80 ingots of precious metal of one grade by making the sides *b b'* of the same depth, dispensing thereby with the recess formed by the unequal depth of the side plates, as above described.

What I claim is—

1. A mold, A, consisting of the back plate, *a*, covered by a stratum of asbestos, *n*, secured by a plate, *a'*, the double sides *b b'*, with asbestos *b' b'* between them, the inner plates, *b' b'*, being 95 of less depth than the outer side plates, *b b*, and the front plate, *c*, with a stratum of asbestos, *m*, and wrought-iron plate *f* at its inner surface, substantially as and for the purpose described.

2. In combination with a mold, A, the sole- 100

plate B, consisting of a bottom plate, *g*, with upwardly-projecting back and front plates, *h*, and stratum of asbestos *w*, and cast-iron plate *v* upon the bottom plate, substantially as and for the purpose set forth.

3. In combination with a mold for producing compound plates of precious metals, the

bar *p*, having a slanting upper surface placed on top of the metal plate, as and for the purpose specified.

ADOLPHUS JOHN LUSTIG.
